UNITED STATES PATENT OFFICE.

LEVI RUTTER, OF NEWMANSTOWN, PENNSYLVANIA.

REFRIGERATOR.

SPECIFICATION forming part of Letters Patent No. 268,434, dated December 5, 1882.

Application filed May 18, 1882. (No model.)

To all whom it may concern:

Be it known that I, LEVI RUTTER, a citizen of the United States, residing at Newmans-
town, in the county of Lebanon and State of
Pennsylvania, have invented certain new and
useful Improvements in Refrigerators; and I
do hereby declare the following to be a full,
clear, and exact description of the invention,
such as will enable others skilled in the art to

10 which it appertains to make and use the same.

My invention relates to refrigerators; and it
consists of parts and combination of parts, all
as will hereinafter be described.

Referring to the drawings, Figure 1 repre-
15 sents a longitudinal vertical sectional view,
Fig. 2 a top plan view, of the ice-box with cover
(broken away) thrown back; Fig. 3, a trans-
verse vertical section.

A represents the box; B, the cover; C, the
20 interior of the box, and D the ice-box.

The box is made with double walls, filled
with any suitable non-conducting material, and
is provided with a door, A', which opens into
25 chamber C. This chamber is provided with
cleats c upon each side to support shelves or
trays c'.

The ice-box is of oblong shape, and is pro-
vided with double or hollow walls, lined inside
with metal, forming a chamber, which serves
30 as a water-vessel, K.

A cock, D³, for drawing off the water is at-
tached to the outer side of the casing and to a
pipe, which connects with a coil, D².

The interior of the box is provided with a
35 metal tray, D', having a slotted bottom, upon
which rests the coil of water-pipes D². One end
of this coil is connected to the water-chamber
K and the other to the pipe passing under the
water-chamber at one side and attached to the
40 cock D³.

To protect the coil of pipes from the ice a
frame, E, is inserted between the coils, as shown
in Figs. 2 and 3.

To the under side of tray D' is attached a
45 number of troughs, I, closed at one end and in-
clined from the front to the rear of the box, for
the purpose of receiving the water from the ice.

Below the lower and open ends of the troughs
is a secondary inclined trough, A², attached to
the rear wall of chamber C, to catch the drip 50
from the inclined troughs I.

To the lower end of trough A² is attached a
waste-pipe, A³, which passes down through
chamber C and the bottom of box A to a suit-
able vessel placed under the box to receive the 55
water.

The bottom of the ice-box is provided with
grooves d, which fit over tongues d' on the top
of box A. Box D is also provided with hooks
d², which catch over lugs d³ on the box A' for 60
an obvious purpose. Cover B is hinged to the
top of the ice-box, and is held in place, when
shut, by a catch, b. Near the center and be-
low handle B' is a vent, B², which allows the
air to escape from the interior of the device. 65

I am aware that it is old to form water-cham-
bers in the walls of a refrigerator, that the
bottom of ice-boxes have been made of pipes
having connections with the water-chamber,
and that inclined troughs have been placed be- 70
low the ice-box to catch the waste-water, which
passes from the inclined trough to a transverse
trough beneath the ends of the first troughs,
and these I do not claim; but

What I do claim is—

An ice-box resting upon and removable from
the walls of a refrigerating-chamber, and hav-
ing a water-chamber open at top in its walls,
a single cover for the ice and water chambers,
a coil of pipes resting upon the slatted bottom of 80
the ice-box, said slatted bottom and a series of
inclined troughs attached to the bottom of the
box, in combination with a refrigerating-cham-
ber having an inclined trough on the ice-box
and provided with a waste-pipe, all substan- 85
tially as set forth.

In testimony whereof I affix my signature in
presence of two witnesses.

LEVI RUTTER.
